UNITED STATES PATENT OFFICE.

PIETER DE LANGE AND ROBERT AERNOUT BARON VAN LYNDEN, OF Utrecht, NETHERLANDS, ASSIGNEES, BY MFSNE ASSIGNMENTS, TO AMERICAN THERMOPHONE COMPANY, OF BOSTON, MASSACHUSETTS, A CORPORATION OF MASSACHUSETTS.

THERMIC TELEPHONE.

1,367,949.

Specification of Letters Patent.

Patented Feb. 8, 1921.

Application filed November 4, 1915. Serial No. 59,627.

To all whom it may concern:

Be it known that we, PIETER DE LANGE and ROBERT AERNOUT BARON VAN LYNDEN, both subjects of the Queen of the Netherlands, and residing at Utrecht, in the Netherlands, have invented a new and useful Thermic Telephone, of which the following is a specification.

Our invention relates to thermic telephones and its object is to provide a thermic telephone which is adapted to be carried upon the person, without a cord, and may be connected to any socket of a telephone system in a house, etc.

According to our invention the thermic telephone is provided with two external plugs mounted on its casing and serving to connect it to the sockets of a system. Consequently, the user of the telephone need carry with him only the telephone proper. Formerly, such telephones had more or less long cords which are not only troublesome when carried in a pocket but also increase not inconsiderably the cost of the telephone.

Reference is to be had to the accompanying drawings in which an example of our invention is shown. Figure 1 is an elevation of a thermic telephone constructed in accordance with our invention, Fig. 2 is also an elevation of the same, but seen at right angles to Fig. 1, and partly in section, Fig. 3 illustrates the connection of the thermic telephone to a socket. Figs. 4 and 5 are sections taken respectively on line A—B in Fig. 3 and on line C—D in Fig. 4, both on an enlarged scale, and Fig. 6 illustrates a manner of carrying the thermic telephone.

Referring to Figs. 1 and 2, the thermic telephone receiver 1 illustrated therein is of the well known construction and of a size enabling it to be introduced directly into the auditory passage of the human ear. The said receiver preferably has at one end a disk-like body 1' with a flat outer surface. The telephone is provided with two external contact plugs 2 mounted directly on the casing adjacent to said flat-faced end or head and conductively connected to the heating wires inclosed within the telephone. The contact plugs 2 are preferably rigid and provided with spherical heads which may receive between them an exchangeable sus-

pension hook 3, by means of which the thermic telephone may be suspended from a pocket, for example, of the waistcoat, as illustrated in Fig. 6.

When the telephone is to be used, its plugs 2 are inserted into a socket 4, preferably having a flat surface adapted to engage the similar surface of the receiver end 1'. Such sockets are suitably distributed over the telephone system and preferably provided with conductor cords 5 of such length as to enable the telephone to be conveniently connected.

A suitable construction of a socket is illustrated in Figs. 4 and 5. It comprises an annular casing 6 provided with openings 7 for the insertion of the plugs 2. The casing 6 is closed by a cover 8 having two crescent-shaped projections or bridges 9 which extend into the hollow space of the casing 6. Between the bridges 9 and the inner walls of the casing 6 are arranged two arc-shaped springs 10, the ends or hooks 11 of which project inwardly slightly beyond the circumference of the openings 7. Connected to the springs 10 are the two current conductors 12 of the cord 5, which lie between the said springs and the bridges 9 and are passed to the outside through a lateral opening 13 of the casing 6. The springs 10 are held in position by means of lateral screws 14. The two parts 6 and 8 of the socket are held together by means of screws or the like, not shown.

When the contact plugs 2 are pushed into the insertion openings 7 of the movable socket 4 they force the ends 11 of the arc-shaped springs 10 outward. The end portions 11 of the springs 10 are practically of the same width as the chamber of the casing 6, see Fig. 5, so that these spring ends will always engage the outer or opposite faces of the ball heads 2, see Fig. 3, thus enabling the parts to be separated readily when desired. The said springs, by their reaction, hold the plugs 2 firmly in the manner of spring-fasteners and establish a reliable connection at the same time, through the screws 14 which not only hold the springs in position but also make contact with the wires 12 as shown in Figs. 4 and 5.

We claim:

1. In a portable telephone, a telephone

casing provided at one end with projecting conducting plugs having free ends, and a socket into which the said free ends are adapted to extend, said socket comprising a 5 casing, bridges located therein and spaced from the inner surrounding wall of the casing, and current-conveying springs extending within the casing between said bridges and said inner wall and having movable 10 portions adapted to engage the free ends of said plugs.

2. In a portable telephone, a telephone casing provided with conducting plugs projecting therefrom, and a socket into which 15 said plugs are adapted to extend, said socket comprising a casing, current-conveying springs arranged within the socket casing and adapted to engage said plugs, wires for connecting said springs with a circuit, 20 and screws having the double function of securing said springs and of making contact with said wires.

3. In a thermic telephone, a casing, a

pair of contact plugs provided with heads mounted on said casing, said contact plugs 25 and heads adapted to extend the talking circuit, said heads also providing a restricted opening whereby the casing may be supported.

4. In a portable telephone, a telephone 30 casing provided at one end with projecting conducting plugs having enlargements, and a socket into which said plugs are adapted to extend, said socket comprising a casing, bridges located therein and spaced from the 35 inner surrounding wall of the casing, and current-conveying springs extending within the casing between said bridges and said inner wall and having movable portions adapted to engage the enlargements of the 40 said plugs.

In testimony whereof we have signed this specification.

PIETER de LANCE.

ROBERT AERNOUT BARON van LYNDEN.
